UNITED STATES PATENT OFFICE.

EDWIN R. THOMAS AND JAMES R. KOEN, OF BUFFALO, NEW YORK,
ASSIGNORS TO E. R. THOMAS MOTOR COMPANY, OF BUFFALO,
NEW YORK.

DESIGN FOR AN AUTOMOBILE-BODY.

SPECIFICATION forming part of Design No. 37,216, dated November 8, 1904.

Application filed October 13, 1904. Serial No. 228,363. Term of patent 7 years.

To all whom it may concern:

Be it known that we, EDWIN R. THOMAS and JAMES R. KOEN, citizens of the United States, residing at Buffalo, in the county of Erie and State of New York, have invented a new, original, and ornamental Design for an Automobile-Body, of which the following is a specification, reference being had to the accompanying drawings, forming a part ¹⁵ thereof.

Figures 1 and 2 are perspective views from

the front and rear, respectively, of an automobile-body, showing our new design.

What we claim as new, and desire to secure by Letters Patent, is—

The ornamental design for an automobile-body, substantially as shown.
